(57) **CLAIM**

The ornamental design for a stuffed animal storage bucket as shown and described.

DESCRIPTION

FIG. 1 is a perspective view of a stuffed animal storage bucket showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a partial enlarged view of portion 9 in FIG. 2.

The dash-dash broken lines depict portions of the stuffed animal storage bucket and form no part of the claimed design. The dash-dot-dot broken lines depict stitching of the zipper and form part of the claimed design. The dot-dash broken lines depict the boundaries of the enlarged view and form no part of the claimed design. The stuffed animal storage bucket is shown with a symbolic break in its length as dash-dot broken lines. The appearance of any portions of the stuffed animal storage bucket between the dash-dot break lines form no part of the claimed design.
